UNITED STATES PATENT OFFICE.

WILLIAM HOUGHTON, OF BATH, MAINE.

DOOR FOR SHIPS' BULKHEADS.

1,078,095.

Specification of Letters Patent. Patented Nov. 11, 1913.

Application filed October 3, 1912. Serial No. 723,757.

To all whom it may concern:

Be it known that I, WILLIAM HOUGHTON, a citizen of the United States, residing at Bath, county of Sagadahoc, State of Maine, have invented certain new Improvements in my Invention of Doors for Ships' Bulkheads, specification forming part of Letters Patent No. 629,790, dated August 1, 1899, application filed October 17, 1898, Serial No. 693,732.

The improvements relate to methods of construction and means for controlling the door automatically.

The object of my invention is to provide simpler means of construction and to make the operation in control of door automatic, instead of having to resort to disengaging and engaging of parts for this purpose.

With these objects in view I confine myself to one type of door that has the opening in the bulkhead always closed. Where it is desired that the divisional bulkheads between large compartments shall be maintained intact such a door is suitable, also as an air lock for passing from one compartment to another when the firerooms are under forced draft aboardship.

The door turns upon a vertical axis coincident with the axis of the casing. The interior face of the casing and the exterior face of the door may be machine-finished, that is to say, they may be turned or ground to produce the most efficient or accurate fit. The door seats itself in its tapered socket or casing, forming a substantially watertight joint.

In the accompanying drawings Figure 1 is a vertical section, Fig. 2, a transverse section therethrough on line 2—2, Fig. 3, a similar section on line 3—3, Fig. 4, a similar section on line 4—4, Fig. 5, an elevation at right angles to Fig. 1 with the lower part of casing broken away showing a side view of the internal gearing at bottom of the door, Fig. 6, a plan view of Fig. 1, Fig. 7, a transverse section therethrough on line 7—7, of Fig. 5, Fig. 8, a transverse section through the upper portion of the socket on the floor of the casing showing the interior of the socket, Fig. 9, a plan view of the gear wheel and pinion on line 9—9.

The improvements in the construction of the casing and the door are as follows, and the parts pointed out to which the improvements relate.

In Fig. 1, X represents a portion of a

ship's bulkhead, an opening is formed therein to which the cylindrical door casing is applied. The casing shown as composed of one part A, is circular in cross section. I provide raised surfaces Z on the outer sides for attaching the bulkhead thereto. The casing tapers from the top downwardly, and at a suitable distance down from the top, and at a suitable distance up from the bottom, opposite openings are formed in the sides which constitute the passage way. At the bottom of the part A, I provide a separate part B' whose circumference and end are continuous or unbroken. A flange f, is formed thereon for connecting to flange f' on part A, which together form the bottom of the door frame. At the top of part A I provide a flat circular shaped part B in one piece, and on the underside of same I provide a circular ring R of a suitable thickness to allow room for raising the door, and forming a positive stop when the door is raised. Part B and the circular ring R are joined together and are secured to flange f² of the part A, which together form a closed cap for the top of the door frame or casing. The door C is a hollow tapering cylindrical body formed with closed ends, having an opening in its side. It fits closely within the casing and turns upon a pivot that is formed on the upper end of the screw C², which I have also combined as a lifting screw for raising the door out of frictional contact with its casing to readily revolve the door with a small expenditure of power, and together with the following is substituted for the conical rolls E and circular track F in the floor of the casing. On the underside of the door I provide a socket S that is internally fitted with a ring E having tapering slots, forming recesses provided with rollers r. On the floor of the door casing also I provide a similar internally fitted socket S'. Journalled in these two sockets is the combination lifting screw C², at the upper end of which a shoulder is formed to support the door when raised. Projecting up through the floor of the door C is the head of the screw C² upon which the door pivots. At the bottom of the screw C² I fit a nut N that is threaded on same, and is circular in cross section.

Referring to the drawings Fig. 4 and Fig. 8, I have shown rings E in the sockets having three tapering slots curved to a suitable radius, and with the screw in place recesses

are formed. In each recess is placed a roller r . The ring in the bottom socket is placed so that the tapering slots point in the opposite direction to those shown in the 5 upper socket, for the purpose when screw C^2 is turned for raising the door, the rollers r in the bottom socket S' will be brought into the narrowing ends of the slots by the nut N , should it attempt to turn with the 10 screw as it naturally will, in which case it will be prevented, as the rollers r will be brought into action by frictional contact with the sides of the slots and body of nut. The screw will then rise and force the door 15 upward without rotating the door, as the rollers in the upper socket S are out of action, being free and kept in the wide end of the slots or recesses by reason of the screw C^2 turning in same direction. When in rotating the door the nut N at the bottom will remain fixed so long as the weight of the door is bearing on same, by frictional contact with the bottom of nut and floor of the 20 casing, permitting the screw to be turned back into its normal position as the rollers in the upper socket are brought into action similar to as described for the rollers in the bottom socket when raising the door. Rollers r in the bottom socket are kept in 25 place by a collar C^3 formed on the body of the screw C^2 . The pitch for the thread on the screw depends upon the height of door to be raised. Thus determined the pitch will then be twice the height, as the door in 30 rotating to bring the opening opposite either opening in the casing requires only half a revolution, so that when the door is rotated after being raised will return the screw back into its normal position and the door also 35 will be brought back into its normal position in its seat. Should the screw C^2 be not raised to the full extent allowed and as the door will always require the full half revolution, the nut and screw can be turned together so as to adjust the opening in the 40 door and casing to coincide. So that it is immaterial whether the door is raised or partly raised. The details thus far and hereinafter described may of course be varied in many ways without departing from the principles of construction and operation hereinbefore indicated.

The means which I have shown for the 45 operation of the door from the outside of the casing are as follows, and replace entirely the means as shown in the previous drawings: Located at a suitable point in the bulkhead I provide a driving shaft which extends through the bulkhead and is 50 equipped at each end with an operating wheel, also on this same shaft is mounted a bevel gear H' adapted to mesh with a similar bevel gear H^2 that is mounted on the vertical shaft H , through the medium of 55 which the vertical shaft is rotated. At the

lower end of the vertical shaft H is mounted thereon a gear wheel I adapted to mesh with a corresponding gear wheel I' that is mounted on a short vertical shaft J that extends upward and through the bottom of the 70 casing. At the upper end of this shaft J there is mounted a pinion gear K adapted to mesh with gear wheel K' that is mounted on the body of the screw C^2 . By the manipulation of the operating wheels on either 75 side of the bulkhead, the screw C^2 may be rotated, which in connection with the door as already described the door may be raised and rotated, turning the operating wheels in one direction for raising and in the opposite direction for rotating the door. For operating the door from within the cylindrical 80 casing I arrange at a suitable place on the wall of the revolving door, a vertical shaft O equipped at the lower end with an operating wheel, and at its upper end there is mounted a pinion wheel M adapted to mesh with a gear wheel M' that is mounted on the projection P that is secured on the underside of part B or cap of the door frame. By the manipulation of the operating wheel 85 the door may be rotated and only in the one direction and is entirely independent from the operating gear provided for controlling the door outside of the casing. The door cannot be raised by this operating gear, and it will be necessary always when the door 90 has to be raised, to use the outside operating gear.

The method in controlling the operation 95 of the door is as follows: Suppose a man in a compartment, on either side of the bulkhead, desires to pass to the other compartment. First he will turn the operating wheel W' or W^2 , as the case may be, to raise the door. Should the opening in the door be in the same compartment, he will then enter the cylindrical door, and by the use of the operating wheel W^3 turn the door around until the opening is brought into the other 100 compartment. Should the opening in the door be in the opposite compartment to where he is, he will first raise the door and then turn it around, to bring the opening so that he can enter, and as the door will have 105 been lowered, caused by turning it around, he should raise it again before entering.

I claim as my improvements as follows:—

1. In a tapering cylindrical door casing and door, mechanism for raising the door out of frictional contact with its casing, comprising the combination of a lifting screw and pivot upon which the door turns, a shoulder on the body of the said screw for supporting the door when raised, a circular nut on the floor of the casing, held in frictional contact to prevent revolving, and the said nut with its screw free to revolve in one direction for adjusting the door opening, a socket mounted on the underside of 110

the door internally fitted with a ring having tapering slots in the form of recesses, one roller in each recess so arranged that said rollers will be thrown out of frictional contact with the sides of the recess and the body of the screw by the movement of the said screw through the medium of the operating wheels on either side of the bulkhead for raising the door, said rollers only being in action when lowering the screw and door together, for rotating the door to bring the opening in the door opposite either opening in the casing.

2. In a tapering cylindrical door casing and door, mechanism for both raising and rotating the door through the medium of the same operating wheels on either side of the bulkhead, a socket on the underside of the door internally fitted with a ring having tapering slots in the form of recesses into

which rollers are positioned so arranged that said rollers will be brought into engagement by frictional contact, put into action by the movement of the screw that is journaled in the said sockets, said rollers freed when the screw is revolved in the opposite direction to permit raising the door without rotating it, a socket on the floor of the casing, arranged internally similar to the socket on the underside of door, a nut on the screw in the said socket in engagement with said rollers so that the door may be raised for rotating to bring its opening opposite either opening in the casing.

In testimony whereof I affix my signature in presence of two witnesses.

WILLIAM HOUGHTON.
